NOISE SUPPRESSOR

John Kelly Johnson, Rye, N. Y., assignor to
Hazelton Corporation, Jersey City, N. J., a corporation of Delaware

Application November 21, 1932, Serial No. 643,652

6 Claims. (Cl. 250—28)

The present invention relates to signal transmission, and more particularly to a "noise suppressor" for automatically controlling the transmission through a signaling system to prevent the reproduction of noises, whether occasioned by atmospheric conditions or produced within the system, whenever the noise intensity is greater than the signal intensity, as for instance, in a radio receiver when tuning from station to station.

This application is a continuation in part of applications Serial No. 603,489, filed April 6, 1932, and Serial No. 603,490, filed April 6, 1932.

The suppression of "noise" signals is accomplished, in accordance with the present invention, by a noise-suppressor arrangement in which the transmission of signals through some portion of the system is controlled in such a manner that when the average signal intensity falls below a predetermined amount, the portion thus controlled will be rendered partially or completely inoperative and thus prevent transmission of the signals therethrough.

The features of this invention are preferably, though not necessarily, incorporated into radio receivers of the usual automatic volume control type, wherein the radio-frequency amplification is automatically controlled in accordance with the average signal intensity.

With a receiver having the usual automatic volume control arrangement, when operating with the manual volume control so adjusted as to give the maximum volume, the sensitivity of the receiver is greatly increased when no signal is being received, as when tuning from station to station. This results in amplifying static and the effect of other atmospheric disturbances to a high degree, causing unpleasant sounds to be emitted from the loudspeaker.

Also, when such a receiver is not tuned to a signal channel and is therefore subject to inter-channel disturbances, it is being operated so that the total amplification is maximum, and the radio-frequency amplifier tubes, while being operated near their practical limit of amplification, cause the reproduction of disagreeable noises by the loudspeaker.

In view of the fact that in the usual automatic volume control receiver the sensitivity of a set is decreased in proportion to the signal intensity, it is necessary to arrange the automatic volume control to have a time delay action to prevent reduction of the low notes of the audio-frequency signal. This time delay action may not permit the reduction of the amplification of the receiver as the tuning crosses the frequency allocations of undesired signals in tuning rapidly through several stations, and may thus cause the loudspeaker to produce a series of loud, unpleasant noises.

It is an object of the present invention to elimi-

nate the above-noted disadvantages of the automatic volume control system, to prevent the reproduction of noise, whether produced by atmospheric disturbances or by the actions of the tubes themselves, and to prevent unpleasant sounds as the receiver is rapidly tuned across the frequency allocations of several stations, as in tuning to a desired signal.

This and further objects will become apparent from the following specification taken in connection with the accompanying drawings.

In accordance with a feature of this invention, a noise-suppressor tube, as it will be called hereinafter, is provided. There is furnished or developed in a circuit associated with the noise-suppressor tube a uni-directional voltage representative of the received signal. This tube is so operated that it serves to reverse the fluctuations of the uni-directional voltage and impress the reversed direct-current voltage fluctuations upon a control circuit of some other tube of the receiver, preferably a tube following the detector, such, for instance, as the second detector tube in a superheterodyne radio receiver, or an audio-frequency amplifier tube. Hereinafter the tube controlled by the noise-suppressor tube will be referred to as the controlled tube.

The characteristics of the suppressor and controlled tubes are so chosen that a substantial change in the voltage of the output of the suppressor tube is obtained by a relatively small variation in the received signal intensity to vary the bias of the controlled tube between a value which will prevent the passage of signal voltage therethrough, or will bias it to cut-off, and a value which will permit normal gain in the system. Thus, when no input voltage due to received signals is impressed upon the suppressor tube the controlled tube is biased to cut-off, thereby preventing signal voltage impressed upon the input thereof from becoming effective in the output circuit. The cut-off bias is ordinarily negative, that is, less positive than is required for normal transmission; hence, when operated in the cut-off condition, the entire controlled system offers in effect a high impedance to the transmission of signal voltages therethrough. Conversely, when an appreciable signal voltage is present, the cut-off bias of the controlled tube is altered, and hence the impedance of the controlled system is in effect lowered, thus permitting the passage of signals therethrough.

It can be seen that whereas, when receiving no signal, the radio-frequency amplifiers of the usual automatic volume control receiver will have the greatest sensitivity, due to the automatic volume control feature, a receiver embodying the present invention will, under the same conditions, have the controlled tube biased to cut-off, and therefore will reproduce no sound impulses.

in the loudspeaker. Whenever a signal of greater than a predetermined intensity is received, the radio-frequency gain is decreased, and simultaneously the bias on the controlled tube is thereby adjusted to the proper value to allow normal amplification.

The arrangement constituting the present invention prevents the production of unpleasant noises when tuning rapidly through several carrier signal frequency channels. This is accomplished by introducing a time delay action into the noise-suppressor circuits so that the cut-off bias of the controlled tube is not removed rapidly enough to let each signal through to produce sounds in the loudspeaker.

A feature is the provision of means for manually controlling the characteristics of the suppressor tube circuit so that any desired input voltage level may be required to cause the controlled tube to operate. This provides a manual control for the "cut-off" level, which term will be employed hereinafter to mean the minimum level at which the suppressor tube will operate to permit reproduction of signals. Thus if the level of noise is high, the cut-off-level control may be operated to raise the cut-off level so that an input voltage greater than the general noise level will be required before the controlled tube will operate. Conversely, if there is a very low noise level, the cut-off-level control may be manually operated to adjust the characteristics of the suppressor tube circuit so that a small input signal voltage will be reproduced.

In order to permit an adjustment of the cut-off level which will not have to be altered while tuning through the frequency band of the receiver, uniform-gain radio-frequency circuits are preferably employed.

Having thus briefly described the present invention, attention is invited to the accompanying drawings, in which:

Fig. 1 is a simplified schematic diagram of a circuit incorporating the invention;

Figs. 2a, 2b, 2c, 2d, 2e, and 2f are diagrams illustrating the operation of the circuit of Fig. 1;

Fig. 3 is a circuit diagram of a more practical embodiment of the present invention;

Fig. 4 is an overload-characteristic curve of a radio receiver for illustrating the operation of a receiver embodying this invention;

Fig. 5 illustrates another embodiment of the invention;

Fig. 6 illustrates an operating characteristic of the arrangement shown in Fig. 5; and

Fig. 7 an arrangement of Fig. 5 in a more complete receiver.

The circuit of Fig. 1 includes a radio-frequency, or carrier-frequency, amplifier 11 which is adapted to amplify the incoming signal and impress the amplified signal upon the input of the diode detector 12. The detected signal is then amplified by a signal translating device which is the audio-frequency amplifier 13, which is the "controlled tube" in the embodiment shown, and the amplification of the detected signal is controlled, in accordance with the present invention, by means of a noise-suppressor tube 14, the operation of which will be explained in connection with the following more detailed description of the circuit arrangement.

The input of the radio-frequency amplifier tube 11 includes a tuned circuit 15 for tuning to carrier-frequency channels, and the output of this amplifier includes the output inductance 20, which is inductively related to the input induct-

ance of the tuned input circuit 21 of the detector 12. The detector output includes the resistor 22, by-passed by the radio-frequency by-pass condenser 23. The resistor 22 and the condenser 23 are so proportioned as to cause the tube 12, which is connected as a diode, to operate as a "peak" detector, as has been described in the above referred to application of Harold A. Wheeler, Serial No. 603,490.

One side of the resistor 22 is connected through resistor 24 to the tuned circuit 15 of the radio-frequency amplifier 11. The output circuit of the amplifier 11 is completed through the high-potential source 25, and a biasing battery 30 is provided to give the grid of the tube the proper bias, as will be explained hereinafter. The detected signals are impressed upon the amplifier 13 through the coupling condenser 31 and resistor 32, the voltage drop across a portion of which is impressed upon the grid of the amplifier tube 13. The amplifier 13 is provided with a grid biasing source 33 and with an output circuit comprising output inductance 36 and high-potential source 37. The inductance 36 is inductively coupled to the inductance 38, which, by means of the terminals 39, may be employed to supply a loudspeaker or the input of further vacuum tube amplifiers. The voltage fluctuations existing across the resistance 22 are impressed directly upon the grid of the noise-suppressor tube 14, the output circuit of which includes the portion of the resistor 32 below the tap 34. Potential source 38 is provided for supplying the plate-potential for the plate of tube 14.

The noise-suppressor tube should have a high amplification factor and should preferably have a sharp cut-off in its grid-voltage plate-current characteristic curve in order that a relatively small change in grid voltage will make a very decided change in the plate current. A type 227 tube is satisfactory for this purpose.

The controlled tube, in this case the audio-frequency amplifier 13, should have a sufficiently high amplification factor that a small change in negative grid bias will bias the tube to cut-off and will stop substantially all plate current. A tube which has been found satisfactory for this purpose is the type 227 tube.

The condensers by which circuits 15 and 21 are tuned may be electrically similar and connected to be simultaneously operated as indicated by the dotted line connecting them in Fig. 1.

In operation, the high-frequency amplifier tube 11 is biased by means of the potential source 30 so that it will have maximum sensitivity with no signal present. The presence of a high average current through the resistor 22 will cause the grid of tube 11 to become more negative relative to the cathode thereof and consequently reduce the amplification of the high-frequency amplifier.

With no radio-frequency signal input to the detector 12, the grid of the noise-suppressor tube 14 will have substantially the same potential as the cathode thereof, and a maximum plate current will flow through the lower portion of the resistor 32. This will cause the point 34 and the grid of the audio-frequency amplifier 13 to be biased so much more negative than the normal bias voltage produced by the bias source 35 that it will be biased to cut-off or past, and no amplification or transmission through this tube will take place when the voltage of the point 34 is fluctuated by the detected currents passing through the coupling condenser 31 and resistor 32. It is thus

apparent that when the grid of audio amplifier 13 is biased more negative under the influence of smaller received signal intensities, its mutual conductance, and hence, amplification decreases; that is to say, its effective internal impedance increases.

Thus, in the condition of no radio-frequency signal, although the amplifier tube 11 is operating at maximum efficiency and the receiver is in its most sensitive condition, as there is very little or no average flow of rectified current through the resistor 22, the bias of the tube 14 will be such that a substantial plate current will be passing through the resistor 32, and the audio-frequency amplifier 13 will therefore be inoperative to transmit stray voltage fluctuations which pass through the detector and are impressed upon the grid of the tube through the coupling condenser 31. If, on the other hand, a signal is impressed upon the detector through the amplifier 11, the average current through the resistor 22, and therefore the average negative voltage at the low end thereof, will increase and the plate current of the noise-suppressor tube 14 will be decreased, thus increasing the voltage at the point 34, that is, making it less negative with respect to the cathode, and permitting the tube 13 to act as an audio-frequency amplifier of the signals impressed thereon through the coupling condenser 31.

It is to be understood that, due to the automatic volume control of the radio-frequency amplifier 11, if there is any substantial signal present at all, the average current through the resistor 22 will be sufficiently high to cut off the plate current in tube 14 and will leave the negative biasing voltage of the point 34 substantially constant over the range of received signal intensities required for normal operation. If, on the other hand, no signal is present, there will be substantially no current flowing through resistor 22, and the point 34 will have a potential which will cause sufficient plate current in tube 14 to bias the amplifier 13 to cut-off.

The specific details of the method shown for obtaining the automatic volume control effect, constitute no part of the present invention, it being understood that any appropriate method may be utilized by which the amplification of the radio-frequency amplifiers and/or the translation gain of the first detector and intermediate-frequency amplifier of a superheterodyne are controlled. The noise-suppressor effect may be obtained by controlling the amplification of any tube or tubes following that which supplies the suppressor tube, such, for instance, as an intermediate-frequency amplifier, second detector, or first or second audio-frequency amplifier of a superheterodyne receiver.

For the purpose of explaining the function of the circuit just described, attention is now invited to Figs. 2a through 2f, inclusive. In Fig. 2a the ordinates represent the radio-frequency voltage in the input of the amplifier 11 (Fig. 1), whereas the abscissas represent the frequency to which the input circuit 15 is tuned. Curve 40a represents the voltage impressed upon the grid of tube 11 as the input circuit is tuned through the frequency of transmission 40 of a signal which is received with medium intensity. Curves 41a and 42a similarly represent the grid voltages of tube 11 as the circuit 15 is tuned through the frequencies 41 and 42 of signals being received with low and high intensity, respectively. Curve 43a represents the voltages impressed upon the tube 11 due to stray atmospheric disturbances and due to tube noises, etc., in the preceding amplifier stages.

Fig. 2b shows a curve 44b, which represents the radio-frequency amplification in the tube 11 as the circuits 15 and 21 are tuned through the range of frequencies covered by Fig. 2a. The portions 43b, which show substantially uniform radio-frequency amplification, indicate the amount of amplification of the ground noise, etc., shown by the curve 43a in Fig. 2a. The portions of the curve 44b designated 40b, 41b, and 42b indicate the decrease in radio-frequency amplification as the circuits 15 and 21 are tuned through the signal frequencies 40, 41 and 42, respectively.

In Fig. 2c the curve 44c represents the peak audio-frequency input to the tube 13. The portions 43c are the peak input voltages resulting from the amplification of the ground noise indicated by curve 43a. The portions 40c, 41c and 42c are the peak voltages produced as the stations 40, 41 and 42 are received. The dotted curve 47 represents the average voltages existing across the resistor 22. Curve 47' indicates the average voltage representative of a much higher ground noise level, as will be explained hereinafter.

As explained above, whenever the voltage across the resistor 22 increases above a certain predetermined value, indicated by a decrease in the radio-frequency amplification at point 45 in Fig. 2b, assuming the circuits to be tuned from left to right, the tube 14 will be biased to cut-off, which will remove the cut-off bias potential of the grid of tube 13. This results, then, in an audio-frequency amplification by the tube 13, which is indicated in Fig. 2d, in which the portions 40d, 41d, and 42d represent the audio-frequency amplification existing as the receiver circuits are tuned through the frequency of the signals 40, 41 and 42 respectively. It will be noted that the sides of the curves 42d, as represented at 45d and 46d respectively, are decidedly abrupt. This abrupt change in amplification takes place as the average detector voltage across the resistor 22 passes points which may be adjusted as desired and which are indicated at 45c and 46c respectively. Between these points on the curve 47, indicating the average voltage across the resistor 22, a signal of relatively uniform intensity is being impressed upon the detector circuit.

In Fig. 2e, the combined amplification of the tubes 11 and 13 is indicated. The portions of the curve 40e, for instance, are represented as being composed of the abrupt rise in audio amplification 40'e, the dip in radio-frequency amplification, 40b, between the points 45e and 46e caused by the decrease in radio-frequency amplification as indicated in Fig. 2b, and the decrease in audio amplification indicated, 40''e.

The audio-frequency output of the receiver is indicated by curves 40f, 41f and 42f, respectively, of Fig. 2f, which curves represent the overall output when tuning through the frequency of signals 40, 41 and 42, respectively.

The cut-off of the audio-frequency tube is determined by the average voltage across the resistor 22, and therefore if the noise is heavy, depending upon the characteristics of the noise-suppressor-tube circuits, sufficient voltage will be built up across the condenser 23 and the resistor 22 to result in a decrease in the bias of the audio-frequency amplifier 13, which will permit the noise to pass through although no station is being received. As above noted, the point at which the tube 14 is biased to prevent its drawing plate current, and thus remove the blocking bias on the tube 13, may be adjusted

manually to suit the particular conditions, which will result in cutting out more or less of the noise. A convenient way of accomplishing this adjustment is by using a screen-grid tube for the noise-suppressor tube 14, and providing an adjustable screen potential. By this arrangement the cut-off may be adjusted so that the required voltage across the resistor 22 to start audio-frequency amplification will not be obtained in the absence of a signal.

A circuit for accomplishing this result is shown in Fig. 3, which circuit is quite similar to that shown in Fig. 1, similar parts being indicated by the same reference characters. This figure differs from the above-described figure principally in the provision of a unitary power supply source, the plate and grid voltage portions of which only are shown. In this circuit, a series of resistors is connected between the high-potential inputs, the negative terminal of which is represented at 49 and the positive terminal of which is represented at 50. The ground of the set is connected to an intermediate point 51. The bias voltage between the grid and cathode of tube 11 is determined by the portion of the resistor 22 between terminal 22' and the right end thereof, resistor 9 and the resistance between terminals 49 and 51. When no signal is being received, the current flowing through the resistance between terminals 49 and 51 will provide the initial grid bias. The bias required for the automatic volume control feature is produced by the detected current flowing through the resistor 22. The grid bias of the tube 14 is provided by means of the entire resistor 22. A resistor 17 is included in the grid lead of the tube 14 to prevent impressing radio-frequency signals on the grid of tube 14, and a by-pass condenser 18 is also provided for this same purpose. A radio-frequency by-pass condenser 55 is also connected between the lower end of the tuned circuit 15 and the cathode of tube 11. The screen voltage potential of the tube 14 may be adjusted, as desired, by means of the variable contact 52 on the resistor between terminals 51 and 53. The contact between the leads from the plate and grid of tubes 14 and 13, respectively, is made variable, as indicated at 34', by means of which the volume output of the receiver may be controlled. The plate circuits of tubes 14 and 13 include resistors 28 and 48 respectively, for the purpose of properly adjusting the potentials of these elements. Appropriate radio-frequency by-pass condensers 27 and 28 are also provided across these resistors. The tap 22' on the resistor 22 may also be connected to preceding high-frequency amplifier tubes, as desired, to permit automatic control of the amplification of such tubes. The circuit of Fig. 3 is primarily intended to include the intermediate-frequency amplifier and second detector of a superheterodyne radio receiver, in which case the circuits 15 and 21 would be tuned to intermediate frequency, and additional radio-frequency amplifier tubes and first detector tubes would be provided, the grid bias potentials of which would be automatically controlled by connection to the tap 22' of the resistor 22.

The high amplification factor of the screen-grid noise-suppressor tube permits a small change in the average voltage across the grid-leak to give a large change in the plate current and therefore a large alteration in the bias of the audio amplifier. Thus, the required change in voltage across the grid-leak being very slight, the audio-frequency amplifier is effectively

turned on and off as the set is slowly tuned through a signal.

The operation of the noise-level cut-off control, which is the most important particular in which this figure differs from the circuit of Fig. 1, will now be described. Referring to Fig. 2c, assume that with the audio-cut-off working at a sensitivity of 0.3 volt as indicated at 45c the noise level is increased above 0.3 to 47'. Then obviously the noise-suppressor tube would be biased to cut-off and the audio amplifier would operate. It is then desirable to decrease the sensitivity of the cut-off control to, say, 0.6 volt as indicated at 45c. To do this, the screen-grid voltage may be manually increased to 2.4 volts by operation of the variable contact 52, which, assuming a grid-screen amplification factor of 8, will then necessitate that the grid be biased 0.3 volt more negative to operate the cut-off of the suppressor tube and cut in the audio amplifier. Then, although the average voltage existing across the grid leak 22 is that shown by curve 47', ground noise will be completely suppressed while tuning between signals.

In further explanation of the operation of the cut-off level control, attention is now invited to Fig. 4, which shows an overload characteristic curve of an automatic volume control radio receiver. The ordinates are output volts from the audio amplifier and the abscissas represent signal input to the antenna, in micro-volts. The curve 60 gives the overall characteristic of a receiver operating in its most sensitive condition. This curve is taken with the noise output filtered out. The curve 60 is that portion of the output due to internal noise which was filtered out in curve 60. The curve 60' gives the total voltage output due to signal and internal noise plotted against input signal voltage.

The curve 61 shows the output of the audio amplifier when the set is operated in a less sensitive condition, as would be the case, for instance, with a "local-distance switch" in the "local" position. As indicated, the sensitivity of the receiver is then so reduced that there is no noise component in the output, attributable to internal noise.

The curve 60-60'-62 shows the output of a receiver employing a noise suppressor, constructed in accordance with the present invention, with the cut-off-level control set, say, for the lowest practical cut-off level. This level has been, in this instance, selected as that at which the result will give an audio output which is half noise and half signal, assuming the most ideal atmospheric condition of absolute freedom from atmospheric disturbances. This corresponds to the condition resulting in the curve 47 of Fig. 2c, where the distance between the base line and the curve between signals represents the audio input resulting from internal noise. This condition gives a sensitivity of about 4 micro-volts. Yet whenever the signal input falls below point 63, corresponding to about 3 micro-volts, the noise suppressor will operate and the controlled tube will allow no signal output.

If now the noise input level is increased to, say 20 micro-volts, indicated at point 64, giving an audio-frequency input as indicated by curve 47' in Fig. 2c, the cut-off level can be raised to point 65 by adjustment of the cut-off level control; and whenever a signal greater than, say, 30 micro-volts is received, resulting in an audio-frequency input, indicated at 45c in Fig. 2c, the audio-frequency output as indicated by curve 75

69-86 will be obtained. Whenever the signal falls below 30 micro-volts, the audio amplifier will be inoperative to transmit signals to the loud-speaker. Thus, if a 100 micro-volt signal is being received, the output to the loudspeaker will be 202 volts, as indicated at 87. On the other hand, with a simple local-distance switch, under the same conditions, the output for a similar signal would be less than 50 volts, as indicated 10 at point 88.

Similarly, if the noise level is greater, the cut-off-level control may be operated to require a signal of 100 micro-volts, indicated at 89, to operate the suppressor tube to cause operation of the reproducing apparatus. The receiver would 15 then operate as indicated by curve 88-70.

The manual volume control is a common arrangement in which any desired portion of voltage fluctuation produced across a resistor included in the output circuit of a detector may be utilized to transmit the signals to the audio-frequency amplifiers. The connection from the plate of the noise-suppressor tube 14 to the resistor 82 may be at any desired point, such, for 20 instance, as at the top thereof, although the arrangement shown has been found quite convenient due to the fact that the portion of the resistor 82 included in the grid circuit of the tube 13 and plate circuit of tube 14 increases 25 as the control is set to higher output volume, thus increasing the biasing cut-off voltage on the grid of tube 13 as increased suppression is 30 needed.

In view of the fact that if the input gain is 35 not uniform the sound level would rise and fall as the receiver is tuned and it could therefore not be efficiently operated with one setting of the cut-off-level control, it is, as above noted, desirable that the input circuits of a receiver embodying this noise suppression invention be 40 of the uniform gain type. Otherwise, the cut-off-level control would have to be varied as the receiver is tuned through its range.

The operation of the circuit of Fig. 3 is in all 45 other respects similar to that of Fig. 1, which has been described in full above.

The usual cathode heating circuits are provided, and any appropriate tubes may be substituted for those shown in both Fig. 1 and Fig. 3, the specific details of none of these elements constituting any part of the present invention.

A variation of the invention is illustrated in Figure 5, wherein the functions of the detector and of the noise-suppressor tube are both performed in a single stage. In this figure, there 55 are shown only the detector and part of the audio-frequency amplifier, these being the essential elements for suppressing the interchannel noise. The carrier frequency signals are impressed upon the tunable circuit 80 of the detector tube 81, and the signals are detected in the usual manner by the detector tube, which is of the three-electrode type operating as a bias type detector having a biasing resistor and a by-pass condenser in the grid-cathode circuit. 60 The bias-resistor is constituted by the series-arranged resistances 85 and 86, shunted by the condenser 87. The output of the detector tube 81 is coupled to the first audio-frequency amplifier tube 82, which in turn, supplies the grids 83 and 84 of a pair of power tubes connected in the well-known push-pull relation. No elements of the power tubes, other than the grids, are shown, as 65 no further discussion of the push-pull action is required, since it constitutes no part of this in-

vention and the arrangement is well understood in the art.

By virtue of the rectifying action of the detector, there is produced in resistors 85 and 86 a uni-directional current which causes the upper terminal of resistor 85 to have a more positive potential than the lower terminal of resistor 86.

The interchannel noise-suppressing action is effected by means of a lead 88 connected between a point of resistor 85 and the screen grid 89 of 10 the first audio-frequency amplifier 82, thereby applying a bias to the screen grid.

When no useful signal is present at the input of the detector there is little or no rectified current flowing through resistors 85 and 86, and consequently, the potential of the screen grid 89 is substantially that of the cathodes, namely, ground potential. Under such a condition, the screen grid acts as an effective shield between the cathode and the anode of tube 82 and substantially 20 prevents the flow of anode current, thereby causing the tube to act as a cut-out relay and prevent audio-frequency reproduction by preventing the audio-frequency current from being impressed upon the push-pull amplifier. In other words, 25 under the condition of zero or very small signal intensity the effective internal impedance between the input and output electrodes of the tube is very great. When, however, a carrier signal is received at the detector of the order of magnitude 30 required for normal operation, the rectified current flowing in resistances 85 and 86 causes the screen grid 89 to become biased positively and thereby permits the tube to function in the normal manner as an amplifier. The audio-frequency signals will then be transmitted to the grids 83 and 84 of the push-pull power stage from whence 35 they may be utilized in any desired manner.

A clearer understanding of the action of the audio-frequency amplifier 82 as a "controlled" 40 tube may be obtained from an inspection of Figure 6, which illustrates the relationship between the gain of the audio-frequency amplifier, plotted as ordinates and the screen grid bias applied to the screen grid 89, plotted as abscissas. It will be 45 observed that when the screen grid bias is increased from zero to an optimum value E₁, the audio-frequency gain rises from practically zero, or "cut-off", to a maximum. Consequently, when 50 no carrier signal is present, the audio-frequency gain is substantially zero, and upon the receipt of signals strong enough to raise the screen grid bias beyond the predetermined "cut-off", the gain rises rapidly to a maximum.

Figure 7 illustrates the interchannel noise-suppressing system of Figure 5 incorporated into a receiver comprising an automatic volume control system operating upon a carrier-frequency amplifier. The complete push-pull power stage and a loudspeaker 91 connected to the output thereof 55 are also shown. That portion of the receiver including the radio-frequency, or carrier-frequency, amplifier is represented by a rectangle 88, since it is unnecessary to illustrate it in detail to bring out the novel feature involved. The carrier-frequency amplifier is shown coupled to the tunable input circuit 80 of the detector 81.

The automatic volume control action is provided by a lead 92 connected between resistors 85 and 86, this lead being connected to a control electrode of one or more of the radio-frequency, or carrier-frequency, tubes (not shown), as indicated in general by the terminal 93. No particular connections are indicated in conjunction 70 75

with these control electrodes, since the manner of connection is well known and constitutes no part of this invention.

In this embodiment, the lead 88 is tapped to a point of resistor 86 instead of resistor 85 as in Fig. 5, this change being made to provide the proper relative potentials for the automatic volume control and the noise-suppressor systems. The cathodes of the carrier-frequency amplifier 10 should preferably be maintained approximately at the potential of the detector cathode. It may also be desirable to isolate the anode-supply potentials of the carrier-frequency amplifier from those of the detector and other tubes. If it is 15 desired that the cathodes of the carrier frequency amplifier be maintained at approximately ground potential, this may be accomplished by employing a separate phase-reversing tube which is connected between the lead 82 and the point 88. 20 Such an arrangement will avoid the use of a separate source of anode potential for the carrier frequency amplifier.

Since, due to the rectifying action of the detector, the upper terminal of resistor 85 is more 25 positive than any other point of resistors 85 and 86, the potential of lead 88 is more negative than the cathode of the detector; hence, the control electrode at 88 is biased negatively (assuming the cathodes of the carrier-frequency tubes to have 30 approximately the potential of the detector cathode). In consequence, the control electrodes of the carrier-frequency amplifier become biased more negatively the greater the received signal intensity, thereby producing the automatic volume 35 control action over a considerable range of received carrier-signal intensities.

The constants of the receiver are preferably so chosen that when the maximum signal strength permitted by the automatic volume control is received at the detector, the bias on the screen grid 40 88 will not rise materially beyond the optimum value indicated in Figure 6 at E'. In case the received signal is rather weak and the carrier-frequency intensity is not strong enough to produce 45 a normal signal current in the anode circuit of detector 81, the audio-frequency gain may be increased by moving the contact of lead 88 to a more positive position on resistor 86. This resistor, or potentiometer thus acts both as a cut-off-level control and as a volume control.

I claim:

1. In a radio receiver, a detector and an audio-frequency amplifier comprising a tube having a cathode, anode, control electrode and a screen 55 electrode, said detector having in its output circuit a resistance across which there is developed a uni-directional voltage dependent upon the intensity of signals applied to said detector, and a connection from a point of said resistance to said 60 screen electrode for causing the transmission through said tube to be greatly reduced when said signal intensity falls below a predetermined value.

2. In a radio receiver, a detector having a cathode-resistor biasing arrangement across which there is developed a uni-directional voltage dependent upon the intensity of signals applied to said detector, an audio-frequency amplifier tube of the screen-grid type coupled to the output of 65 said detector, an automatic volume control arrangement for maintaining the signal strength

at said detector substantially constant over a wide range of received signal intensities, and a connection from a point of said resistor to the screen grid of said audio amplifier for causing said amplifier to become practically unresponsive 5 when the intensity of signals at said detector falls below a predetermined value below said range.

3. In a radio receiver, a carrier-frequency amplifier, a detector coupled to the output of said carrier-frequency amplifier, and an audio-frequency amplifier having a screen grid, coupled to the output of said detector, said detector having a cathode, anode and control electrode and having in series between said cathode and control electrode a resistance shunted by a condenser, whereby rectification of carrier-frequency signals occurs, means for automatically controlling the volume of the signals impressed upon said detector, whereby the intensity of signals at said detector is maintained substantially constant over a wide range of received signal intensity, and a connection from a point of said resistance to said screen grid for rendering said screen grid less positive when the signal intensity at said detector 20 falls to a relatively small value.

4. In a radio receiver, in combination, a carrier-frequency amplifier, a detector coupled to the output of said amplifier, said detector being of the vacuum-tube type having a cathode, anode 30 and grid, a second amplifier coupled to the output of said detector, said second amplifier comprising a vacuum tube having an anode, cathode, control grid and a screen grid, said detector having in its cathode-grid circuit a resistance shunted 35 by a condenser for producing the detecting action, and a connection from a point of said resistance to said screen grid, the polarity of said connection being such that said screen grid becomes biased less positively when the signal 40 strength falls below a predetermined value, whereby interchannel disturbances are substantially reduced.

5. A combination according to claim 4 in which the cathode of said second amplifier is grounded 45 and said resistance is connected between said detector cathode and ground.

6. In a radio receiver, in combination, a carrier-frequency amplifier, a detector coupled to the output of said amplifier, said detector being of the vacuum-tube type having a cathode, anode 50 and grid, a second amplifier coupled to the output of said detector, said second amplifier comprising a vacuum tube having an anode, cathode, control grid and screen grid, said detector having 55 connected in its cathode-grid circuit a resistance across which a uni-directional detected voltage is developed, automatic volume control means associated with said carrier-frequency amplifier for maintaining the output of said detector substantially constant over a wide range of received signal intensity, and a connection from a second point of said resistance to said screen grid for biasing said screen grid less positively and thereby rendering said second amplifier 60 substantially unresponsive when the signal strength falls below a predetermined value below said range, said second point of said resistance being at a more negative uni-directional potential than said first point.

JOHN KELLY JOHNSON.
